UNITED STATES PATENT OFFICE.

WILLIAM WALLACE, OF BAKERSFIELD, CALIFORNIA.

OIL-WELL PUMP.

No. 876,118.

Specification of Letters Patent.

Patented Jan. 7, 1908.

Application filed December 8, 1906. Serial No. 346,870.

To all whom it may concern:

Be it known that I, WILLIAM WALLACE, a citizen of the United States, residing at Bakersfield, in the county of Kern and State of California, have invented new and useful Improvements in Oil-Well Pumps, of which the following is a specification.

My invention relates to certain new and useful improvements in oil well pumps and particularly in a removable interchangeable bushing for the working barrel thereof, and a means for removing the bushing in unison with the working parts of the pump from their containing cylinder or barrel without removing said cylinder or barrel from the well.

My invention further relates to means for locking the removable bushing in place in the barrel; also in means for seating the standing 20 value of the pump in its barrel.

My invention consists, essentially, of a readily removable bushing which is normally locked in position in the barrel but which, when the working parts of the pump are to be removed, is released from its locked position during the initial part of the withdrawal of the said working parts and is then removed by and in unison with said parts, without disturbing the cylinder or barrel.

My invention also consists of suitably spring - pressed latches which engage the bushing to retain it in proper position in the barrel but which will yield to release the bushing to allow said bushing to be removed 35 by and with the working parts.

My invention further consists of the parts and the constructions, arrangements and combinations of parts which I will herein-after describe and claim.

In the accompanying drawing forming part of this specification, Figure 1, represents a vertical sectional view of an oil well pump embodying my invention. Fig. 2, is a detail of one of the striking blocks. Fig. 3 is an enlarged sectional detail of one of the pins 43 and a portion of the bushing 40.

In said drawings the standing barrel 10 is preferably made of cast iron although other character of material may be used if desired. 50 Its lower end has fitted to it a pipe section 11 which may represent the lower or suction end of the pump barrel said barrel having a tapering valve seat 12.

Within the standing barrel is the standing 55 valve 13 which is suitably packed to snugly

fit the interior of the barrel, said valve having a tapered lower end to fit the aforesaid tapered valve seat 12, and having a passage through it, as usual, for the flow of oil. Connected to the upper end of the standing valve 60 is a suitable cage 14 and within said cage is a ball or other valve 15 which seats upon a valve seat 16. This seat may be of any well known character: It is herein shown as being of the reversible type or capable of using 65 either side uppermost, and it is held securely in place between a shoulder 17 on the cage and the top end of the standing valve, the seat having a circumferential flange which is clamped between these said surfaces. 70

The upper end of the standing barrel has an enlarged socket or chamber 18 to which is fitted, as by screw threads between the parts, the lower end of the cylinder or barrel 19 which I will hereinafter designate as the intermediate barrel, said intermediate barrel having its upper end screwed into engagement with the lower collar 20. The opening through this collar is cored out in the upper end to form an enlarged socket in which is 80 screwed the lower end of the cylinder or jacket 21 whose upper end is screwed into engagement with the upper collar 22.

The jacket and intermediate barrel may be constructed of steel or iron pipe and will have 85 such length and diameter as the particular well may require.

The hollow pump plunger 23 is of slightly less diameter than the interior of the intermediate barrel 19 in which it operates. Its 90 lower end is threaded to a ring 24 of increased thickness, the lower end of which is adapted to seat upon a striking block 25 of substantially triangular form or a block whose edge is cut away at points to accommodate the 95 flow of oil, said block being seated upon the top of the cage of the standing valve and fixed thereto by means of the rod 26 whose lower end is threaded and screws through said block 25 and into the top of said cage, a 100 nut 27 being shown for the purpose of maintaining the parts in their proper position after being once fitted together as described.

By reason of the arrangement just above described it is apparent that in assembling 105 the parts of the pump, the lower end or ring 24 of the plunger will strike the block 25 and thereby positively seat the standing valve upon the inclined seat 12 in the standing barrel. The rod 26 before mentioned, extends 110

from the cage of the standing valve upwardly into the plunger for such distance as may be desired, and to its upper end is screwed or otherwise fixed a striking block 28 which is 5 designed to be engaged from below by the shoulder 29 of the ring 24 when the plunger is to be removed from the pump and it is desired to remove the standing valve and its adjuncts also.

10 The upper end of the plunger is fitted to a nipple or coupling 30 to which the upper valve cage 31 is also fitted, said cage inclosing the upper valve 32 which normally rests upon a valve seat 33, substantially of the 15 form of the seat already described for the valve 15, said cage having a threaded stem or projection 34 at its upper end adapted to be engaged by the lower end of a connection or coupling 35 carried by the lower end of the 20 adjusting rod 36, said rod having a flange or shoulder 37 just below its upper threaded end upon which flange the striking block 38 is seated, and held by the lower end of the suction rod 39 being screwed upon the threaded 25 stem extension of the adjusting rod.

The striking block 38 is substantially like the blocks 25 and 28 and is designed to rest upon the upper end of the bushing 40 in which bushing the pump plunger operates 30 with a snug sliding fit. This bushing and the manner of detachably securing it forms the essential part of the present invention. It is made of cast iron or any other suitable material and fits snugly the interior of the jacket 35 21 and forms the renewable wearing surface therefor. The bushing may be of any desired length and thickness; as shown, it extends between the top and bottom collars 22 and 20 and its lower end enters the enlarged 40 socket in the upper end of the lower collar and its lower end is beveled or tapered to snugly fit a corresponding seat 41 in the base of said socket and the lower edge extends into the opening made through the bottom 45 collar for the passage of the plunger, which plunger, as before mentioned, is of somewhat less interior diameter than that of the intermediate barrel 19 in which it operates. The result of this construction is, that the lower 50 edge of the bushing lies in the vertical plane of the projecting outer edge of the lower striking block 25 and will be engaged thereby when said block and its connected standing valve and adjuncts are lifted by the plunger 55 to effect their removal from the pump barrel or cylinder.

Referring now to the upper collar 22, it will be seen that one or more holes 42 are bored transversely therethrough, and in 60 these holes are placed headed-pins 43 backed by spring 43'. The holes are closed by screw or other plugs 44 against which the springs seat; and the inner ends of the pins engage an annular channel or groove 45 formed around 65 the outside of the bushing near the upper

end, but which pins will yield to release the bushing when said bushing is moved in an endwise direction.

From the foregoing description it will be understood that to assemble the working parts of the pump, after the standing barrel, intermediate barrel, and jacket have been coupled together and lowered to position in the well, the bushing is placed in the upper section of the pump barrel or cylinder and the sucker rod to which has been appropriately coupled the adjusting rod 36 plunger 40 and standing valve 13, and their accessories, is lowered into the pump cylinder until the striking block 38 at the lower end of the rod 36 strikes the top of the bushing and finally shoves the bushing through the top collar and into the jacket 21 of the working barrel until the lower tapered end of the bushing comes to a firm seating upon the inclined 85 seat 41 formed in the bottom collar 20, and the channel or groove 45 around the upper end of the bushing is brought into register with the spring-pressed pins 43 when said pins will enter the channel or groove and 90 lock the bushing in place. Coördinately with this seating the bushing, the lower end of the plunger 23 strikes the block 25 on the upper end of the cage of the standing valve and thereby firmly seats this valve upon the 95 tapered seat 12 in the standing barrel.

To withdraw the plunger and other working parts, the sucker rod is lifted, and through connections substantially as shown and described, the plunger is raised until the 100 upper end or shoulder 29 of the ring 24 which is fixed to its lower end contacts with the under side of the striking block 28 on the upper end of the rod 26 when the standing valve is raised from its seat. At or about this time, 105 the projecting or outer edge of the striking block 25 on the lower end of the rod 26 comes in contact with the lower edge of the bushing and the continued upward pull on the sucker rod and endwise movement of the bushing 110 causes the spring-pressed pins 43 to be forced back thereby disconnecting them from the annular groove or channel 45 and allowing the bushing to be readily removed with the other working parts of the pump, for repair 115 or for renewal of parts. The bushing is thus interchangeable and may be removed and replaced with but little difficulty, and by and in unison with the other working parts.

Having thus described my invention, what 120 I claim as new and desire to secure by Letters Patent is,—

1. In an oil well pump, the combination of a working barrel, a bushing removably seated therein and closely fitting the same, a 125 plunger operable in the bushing, a standing-valve-mechanism, means carried by the plunger for unseating the standing-valve and supporting it from the plunger, and a striking-member carried by the standing-valve and 130

projecting beyond the plane of the outer sides of the plunger, said bushing having a part projected into the vertical plane of said striking-member and adapted to be engaged thereby whereby said bushing is unseated and removed by and in unison with the plunger and standing-valve-mechanism.

2. In an oil well pump, the combination of a working barrel, a bushing removably seated therein, yieldable means engaging the bushing to lock it in the barrel, a plunger operable in the bushing, a standing-valve-mechanism, means carried by the plunger for unseating the standing-valve, and suspending it from the plunger, and a striking-member carried in unison with the plunger and standing-valve, said member adapted to engage the bushing to first unlock it and then move it lengthwise and finally remove it from the barrel coördinately with the removal of the plunger and standing-valve-mechanism.

3. In an oil well pump, the combination with the working barrel thereof, the removable plunger and the standing - valve, of normally-separated contacting members one carried by the plunger and the other carried by the standing-valve, said plunger member contacting with the other member when the plunger is elevated for removal, and unseating the standing-valve and suspending said valve from the plunger, and normally-separated contacting members one on the bushing and the other carried by the plunger, said plunger - carrying - member contacting with the bushing-member to first unseat the bushing and then remove it from the barrel in unison with the removal of the plunger.

4. In an oil well pump, the combination with the exterior cylinder or jacket and the upper and lower collars to which its ends are secured, said lower collar having an internal bushing seat, a bushing fitting within the jacket with its lower end resting upon said seat, and its lower edge projecting interior thereto, a plunger fitting the bushing, said plunger carrying a striking-member which is adapted to contact with the projecting edge of the bushing when the plunger is lifted for removal, yieldable latches mounted in the upper collar and normally engaging the bushing to hold it to its seat, said latches yielding to release the bushing under the pressure exerted by the plunger striking-member against the lower end of the bushing whereby the plunger and bushing may be removed in unison.

5. In an oil well pump the combination of the standing barrel, the intermediate barrel

fitted thereto, the lower collar to which the upper end of the intermediate barrel is fitted, an upper collar, a jacket extending between and having its ends fitted to said upper and lower collars, a bushing fitting within the jacket and having an interior diameter less than that of the interior of the intermediate barrel, a seat formed on the interior of the lower collar for the lower end of the bushing, said bushing having its lower edge projecting inwardly of the seat, a plunger and plunger suspending connections, said plunger fitting the bushing and having an annular shoulder on its interior near the lower end, a standing-valve adapted to be seated in the standing barrel, said valve having a stem or rod fixed to its upper end and extending into the plunger, a striking-block fixed to the upper and lower ends of said stem, said lower block having a greater diameter than that of the exterior of the plunger and sufficient diameter to allow it to contact with the lower edge of the bushing when raised to the plane thereof, the lower end of said plunger adapted to contact with said lower block to seat the standing-valve in its barrel, and the internal shoulder of the plunger adapted to engage the upper striking-block to unseat the standing-valve, the arrangement of the parts being such that the plunger and standing-valve and their adjuncts and the bushing are removable from the working barrel of the pump in unison.

6. The combination of the barrel, a bushing fitting the same, upper and lower collars, said lower collar having an internal seat for the lower end of the bushing, and said bushing having a channel or groove around its upper portion, spring-pressed locking-pins in the upper collar adapted to engage said channel or groove, to lock the bushing on its seat in the lower collar, a plunger operable in the bushing and means carried by the plunger adapted to contact with the bushing to unseat the same and disengage the locking-pins, an adjusting-rod connected to the plunger, a sucker-rod connected to the adjusting-rod, and a striking-block fixed to or carried in unison with the adjusting-rod and adapted to contact with the upper end of the bushing to seat said bushing.

In testimony whereof I have hereunto set my hand in presence of two subscribing witnesses.

WILLIAM WALLACE.
